UNITED STATES PATENT OFFICE.

JOHN F. MYERS, OF HIAWATHA, KANSAS.

CAR-STEP.

No. 837,242.

Specification of Letters Patent.

Patented Nov. 27, 1906.

Application filed May 6, 1906. Serial No. 259,166.

To all whom it may concern:

Be it known that I, JOHN F. MYERS, a citizen of the United States, residing at Hiawatha, in the county of Brown and State 5 of Kansas, have invented new and useful Improvements in Car-Steps, of which the following is a specification.

The invention relates generally to an improvement in car-steps, and particularly to an extensible step designed for an adjustable connection with the ordinary railway-car step.

The main object of the invention is the production of an extensible car-step designed 15 for slidable and adjustable connection with the ordinary car-step and adapted when in lowered position to serve as an additional or lower step for the convenience of passengers.

The invention in its preferred form will be 20 described in the following specification, reference being had to the accompanying drawings, in which—

Figure 1 is a perspective view of a car-platform, illustrating the application thereto 25 of my extensible car-step. Fig. 2 is a sectional view of the platform, illustrating the rear elevation of my improved extensible step and connecting parts. Fig. 3 is a transverse section taken through the ordinary 30 car-steps, showing my extensible step connected therewith and in closed position.

Referring to the drawings, wherein like numerals of reference designate like parts throughout the specification, 1 represents a 35 car-platform, from the opposite ends of which depend the usual steps 2, supported in hangers or side frames 3.

My improved extensible step comprises a tread-platform 4, secured at the lower end of 40 slide-bars 5, the upper ends of which bars are connected by a transverse bar 6. The slide-bars 5 are movably connected with the rear face of the steps proper, as shown. By preference suitable filler-blocks are manipulated 45 to fill up the rear face of the step-carriages to provide a straight inclined surface to receive the slide-bars, each of said filler-blocks being preferably provided with a strap 8, centrally bent to form a guideway 9 to 50 receive the slide-bars. The guides 9 are arranged in alinement to receive the slide-bars, so that in the operation desired said bars move vertically with relation to the steps proper to protect the extensible step below 55 the steps proper or to draw the same in contact with the lower step.

A lever 10 is pivotally connected to one of the step-hangers 3, as at 11, being centrally enlarged at 12 and formed with a longitudinal slot 13 to receive a pin 14, projecting laterally from the cross-bar 6, connecting 60 with slide-bars 5. The handle end 15 of the lever projects beyond one of the step-hangers 3 for convenience in operation, said step-hanger being provided with means for securing the lever in adjusted position. By preference I prefer to provide a tooth-bar 16, terminally secured with the step-hanger and spaced therefrom intermediate its end. The lever operates between said bar and 70 step-hanger, and the bar is provided with a series of teeth 17, arranged to receive and engage said lever, the teeth being formed to hold the lever against downward movement without interfering with its convenient upward movement. Guide-bars 18 are secured to the respective ends of the extensible step 4, being longitudinally slotted at 19 to engage pins 20, projecting from the outer side of said step-hangers 3, whereby the extensible step is effectively guided in operation. 75

In operation the lever 10 is suitably manipulated to elevate or lower the slide-bars 5, and thereby project the extensible step below the last step of the usual series or drive said 80 extensible step into contact with said last step. The arrangement of the slide-bars 5 is such that when said extensible step is not in operative position, as illustrated in Fig. 3, it will rest snugly against the lower surface 90 of the last step of the series proper without projecting portions, whereby it is normally supported entirely out of the way. By engaging the lever with the desired tooth 17 of the bar 16 the step 4 may be supported at 95 any distance below the last step of the series, permitting the extensible step to be adjusted in accordance with the varying height of the track-platforms. The slide-bars 5 project transversely beneath and are coextensive 100 with the full width of the extensible step 4, whereby said step is effectively supported against possibility of disconnection.

I do not desire to limit myself to the previous construction herein described and 105 shown, and various modifications and changes therein may be made without departing from the spirit of my invention.

It may be found desirable to operate the lever 10 from the car-platform, in which 110 event said lever may be connected through the medium of a link 21 to the arm of a right-

angle lever 22, pivotally supported on the car-platform and arranged for operation to adjust the step, as clearly shown in dotted outline in Fig. 1.

5 It is to be understood, of course, that while I have shown and described my adjustable step in connection with railroad-cars it is evident that it is equally applicable to motor-cars, automobiles, street-cars, coaches, and in other situations in which an extensible step is desirable.

Having now described my invention, what I claim as new, and desire to secure by Letters Patent, is—

15 1. The combination with car-steps, of an additional tread, slide-bars connected to said tread and adjustably connected with the steps, a slotted lever pivotally and slid-

ably connected with said slide-bars, and a tooth-bar arranged to engage and lock said lever in adjusted position.

2. The combination with car-steps, of an additional tread, slide-bars connected to said tread and adjustably connected with the steps, a slotted lever connected with 25 said slide-bars, a tooth-bar on one of the step-hangers, and arranged to engage and lock said lever in adjusted position, and guide-rods connected with the ends of the tread and slidably engaging the step-hangers. 30

In testimony whereof I affix my signature in presence of two witnesses.

JOHN F. MYERS.
